B. BENEDICT,
PORTABLE ELECTRIC LIGHT,
APPLICATION FILED MAY 11, 1917.

1,315,457.

Patented Sept. 9, 1919.

Inventor
Bernard Benedict
By his Attorney
Henry D. Williams

UNITED STATES PATENT OFFICE.

BERNARD BENEDICT, OF NEW YORK, N. Y., ASSIGNOR TO NATIONAL CARBON COMPANY, INC., OF NEW YORK, N. Y., A CORPORATION OF NEW YORK.

PORTABLE ELECTRIC LIGHT.

1,315,457.

Specification of Letters Patent.

Patented Sept. 9, 1919.

Application filed May 11, 1917. Serial No. 167,888.

To all whom it may concern:

Be it known that I, BERNARD BENEDICT, a citizen of the United States, residing at New York city, in the county of Bronx and 5 State of New York, have invented certain new and useful Improvements in Portable Electric Lights, of which the following is a specification, reference being had therein to the accompanying drawings, forming part 10 thereof.

My invention relates to self-contained or battery-operated portable electric lights and relates more particularly to the flat type of these lights. An object of my invention is 15 to provide such a light of simple and inexpensive construction which has a large number of uses and advantages, which will hereinafter appear in detail.

My invention includes novel means for 20 holding the battery in the casing and for completing the circuit of such battery to a miniature incandescent lamp supported by and exposed at the outside of one of the flat sides of the battery-containing casing. My 25 invention also includes a mirror forming an outer surface of one of the sides of the battery-containing casing combined with a lamp adapted to illuminate an object reflected in the mirror. My invention more 30 particularly includes a miniature incandescent lamp and a mirror both fixedly or rigidly supported by and exposed adjacent to each other at the same side of one of the flat sides of the battery-containing casing. My 35 invention also includes in combination particular features of construction and combinations of parts as will appear from the following description.

I shall now describe the portable electric 40 light embodying my invention illustrated in the accompanying drawings and shall thereafter point out my invention in claims.

Figure 1 is a front elevation of the complete device.

Fig. 2 is a central longitudinal section on 45 a vertical plane indicated by the line 2—2 of Fig. 1 as viewed from the left, the battery being omitted.

Fig. 3 is an elevation of the complete device as viewed from the left in Fig. 1, but with the device inclined rearwardly and the bail partly extended so as to act as a support or prop therefor.

Fig. 4 is a front elevation of the complete 50 device with the casing partly open and with

the bail fully extended and with parts of the bail omitted.

Fig. 5 is an enlarged partial longitudinal section on an inclined or diagonal plane indicated by the line 5—5 of Figs. 3 and 4, as 60 viewed from the right and slightly toward the rear in Fig. 3 and as viewed from the front and slightly from the left in Fig. 4.

Fig. 6 is a partial transverse section of the 65 rear casing part on a horizontal plane indicated by the line 6—6 of Fig. 4, and illustrates the spring battery-holding clip.

Fig. 7 is a partial longitudinal section on a plane indicated by the line 7—7 of Fig. 3 as viewed from the right, illustrating the 70 friction means for the pivoted bail.

Fig. 8 is a perspective view, before its attachment, of the combined battery-supporting and contact-making device, carried by 75 the rear casing part at the top of the battery.

Fig. 9 is a partial longitudinal section on a plane indicated by the line 9—9 of Figs. 4 and 8 as viewed from the left.

Fig. 10 is a similar view on a plane indicated by the line 10—10. 80

The portable electric light embodying my invention illustrated in the accompanying drawings has a rounded substantially rectangular elongated flat sheet metal casing which is divided in a plane passing midway between and parallel with the flat sides thereof, or in the plane of its largest dimensions, into two similar halves or casing parts 1 and 2, of which the rear half 1 may be designated as the battery-supporting casing part, 85 and of which the front half 2 may be designated as the lamp-carrying and mirror-providing casing part. The casing parts or halves 1 and 2 are pivotally united by means of a hinge 3 which is shown as pivotally connecting or hinging together adjacent longer edges or margins of the casing parts 1 and 2 and which, in the construction illustrated in the drawings, appears at the right when the device is viewed from the front, as 90

in Fig. 1. The free edges or margins of the casing parts 1 and 2 opposite to the hinge 3 are provided with a snap catch or latch of usual form and shown as comprising a leaf spring 4 secured at the inside of the margin 95 of the front casing part 2 by means of a rivet 5 at its upper end and provided at its lower end with a thumb piece 6 projecting to the outside of the casing part 2 through a slot therein, and adjacent to its lower end 100

105

110

the leaf spring 4 is also provided with a lateral perforated extension 7 forming a catch adapted to engage with an inner projection 8 at the inside of the free margin of the rear casing part 1 and formed by indenting inward the metal thereof.

In the construction of portable electric light illustrated in the drawings as an embodiment of my invention, the battery-supporting means and the circuit-completing means are in part combined and are located in or carried by the rear casing part 1. The flat sheet metal casing, comprising the two hinged parts or halves 1 and 2, contains a usual flat form of dry battery 9 which has the usual spring contact terminals 10 and 11, of which the contact spring or contact strip 10 is of the usual short upright form, and the other contact spring or contact strip 11 is of the usual transversely and angularly upwardly extending longer form.

A manually actuatable circuit controller of substantially usual form is shown as provided for electrically connecting the short upright battery terminal 10 with the rear or battery-holding metallic casing part 1. A spring contact strip 12 is secured at its lower end, for example, by means of solder, to the inside of the margin of the rear casing part 1 and at its upper end is turned inwardly toward but normally out of contact with the upright battery terminal 10. At an intermediate point the contact spring 12 is shown as provided with a usual battery-spacing loop 13. Above the loop 13 the contact spring 12 is provided with a push button 14 projecting to the outside of the casing part 1 for manual actuation. Also the contact spring 12 is adapted to be actuated by means of a slide 15 guided in a usual way on the casing part 1 and adapted to override the projecting rounded end of the push button 14 in a usual way.

At its lower end the battery 9, which has the usual outer insulating covering, rests upon and is supported by a battery-supporting ledge or shelf 16, which is shown as formed from a strip of sheet metal bent at right angles on a rounded curve to provide a rounded battery-supporting surface, as appears in Figs. 2 and 4 of the drawings, this lower battery-support 16 being suitably secured to the inside of the rear casing part 1, for example, by soldering.

The battery 9 is further supported and is securely held within the rear casing part 1 in the open condition of the casing, appearing in Fig. 4, by means of a bent spring clip 17 secured, for example, by means of solder, to the inner margin of the rear metallic casing part 1 and resiliently engaging and gripping the edge and partly at the front of the margin of the battery 9, as will be clear from Figs. 4 and 6 of the drawings. It will be noted that this spring battery-holding clip

17 not only prevents the battery 9 from falling out of the battery-holding casing part 1 in the open position of the cover part 2, but also this spring clip 17 pushes or presses the battery toward the hinged side of the casing and effectually prevents accidental shifting movement of the battery 9 which might bring its short upright contact terminal 10 into circuit-closing or contact-making relation with the inturned end of the contact spring 12 in the normally open circuit position of the latter.

A metallic screw-threaded lamp socket 18, forming also a reflector, as clearly appears in the drawings, is fixedly carried by the front casing part or casing half 2 at the upper margin of the flat part thereof so as to be directed or to open outwardly from the flat side of the casing, and this lamp socket 18 is shown as formed of a separate piece which is soldered in place in an opening in the upper margin of the flat side of the front casing part 2, as appears in the drawings. A usual miniature incandescent lamp, having a bulb 19 exposed at the outside of the flat side of the front casing half 2, has a usual annular screw-threaded metallic base terminal 20 screwed into the lamp socket 18, and a usual central terminal 21 exposed at the inside of the casing above the battery 9 but, by reason of the transverse position of the lamp, the central terminal 21 is not in position to be engaged by the long transversely extending spring battery terminal 11.

A combined battery-supporting and circuit-completing device is carried by the rear casing part 1 at the top of the battery 9 so as to form at this point an abutment for the upper end of the battery 9 and also, in the closed condition of the casing, is adapted to complete the electrical connection between the transversely extending longer battery terminal 11 and the central terminal 21 of the lamp. A substantially L-shaped and generally vertically arranged bent sheet metal battery support 22 is of comparatively rigid construction and at its lower outwardly projecting end engages above and holds the longer spring battery terminal 11 in a depressed position. In its upper part the battery-holding metal strip 22 is conformed to the interior curve of the upper margin of the rear casing part 1 and is secured thereto but is insulated therefrom. Two superposed layers or thicknesses 23 and 24 of electrically insulating material are interposed between the battery-supporting member 22 and the adjacent inner surface of the metallic rear casing part 1. The metallic battery-supporting metal strip 22 is firmly and rigidly secured to the inwardly exposed insulating layer 23 by means of metallic rivets 25 and 26, shown as of the tubular type, and these metallic rivets 25 and 26 are insulated from the casing part 1 by the other interposed in-

sulating layer or plate 24. The two insulating plates 23 and 24 are secured together by means of tubular metallic rivets 27, of which two are shown, and these superposed insulating plates 23 and 24 are firmly secured to the inner surface of the metallic casing part 1 by means of plugs 28 of solder contained within the tubular rivets 27, as appears most clearly in Figs. 2 and 9 of the drawings.

10 The comparatively rigid battery-supporting abutment member 22 is provided with a comparatively flexible resilient contact spring 29 which is carried by and projects laterally from the battery-holding abutment member 22 to which it is shown as firmly secured at one end by means of the lower rivet 26. The projecting free end part of the circuit-completing contact spring 29 projects laterally in offset relation from the 20 battery-supporting member 22 and in spaced relation to the adjacent insulating plate 23 and is disposed in the path of and adapted to be engaged by the central terminal 21 of the lamp when the casing is in the closed 25 condition as appears in Fig. 2 of the drawings. It will now be clear that the continuity of the battery circuit is completed or preserved from the longer transverse spring battery terminal 11 through the electrically conductive battery-supporting member 22 and resilient contact spring 29 to the central terminal 21 of the lamp.

A mirror 30 is fixedly or rigidly carried by the front casing half or front casing part 35 2 and is exposed at the outside of the flat side thereof. The mirror 30 is thus exposed at the outside of the flat side of the front casing part or cover part 2 through an opening cut therein, as appears in the 40 drawings, this opening being of slightly smaller dimension than is the mirror 30, and the sheet metal which forms the flat casing part or cover part 2 is embossed or pressed outward around the mirror-receiving 45 opening to form a frame for the mirror. This mirror-holding frame includes a marginal flat part or flange 31 which overlaps upon the outer edges or margins of the mirror 30, in the construction shown in the 50 drawings these margins of the mirror 30 being shown as beveled, as appears in Figs. 1 and 2 of the drawings. The mirror-engaging flange 31 of the mirror frame is offset outwardly from the adjacent flat part of the casing cover 2 and is joined thereto by an inclined side part 32, so that the back of the mirror is substantially flush or in the same plane with the inner surface of the adjacent flat front part of the casing cover 60 2, as most clearly appears in Fig. 2 of the drawings. The mirror 30 is firmly and rigidly held in place in its frame, comprising the flange 31 and inclined side part 32, by means of a metallic backing plate 33 65 which completely covers and supports the

mirror 30 at the back at the inside of the casing cover part 2, the edges or margins of this backing plate 33 overlapping upon the inner flat surface of the cover part 2 and being soldered thereto.

It will be noted that the mirror 30 and the incandescent lamp, having the bulb 19, are both firmly and fixedly mounted on and carried by the front casing part 2 and that the mirror 30 and lamp bulb 19 are both 70 exposed at the outside of the front or flat side of the casing, so that objects which are in position to be reflected in the mirror 30 will be illuminated by the lamp bulb 19. It is also to be noted that the lamp bulb 19 75 and mirror 30 are always exposed at the outside of the casing in position for instant use, either separately or in combination.

A foldable bail 34 is frictionally pivoted to the rear casing part 1 so as to be extended 80 rearwardly outwardly and upwardly angularly therefrom. The bail 34 is formed from suitable spring wire and is shown as adapted to be frictionally held in desired adjusted position by means of conical pivot 85 ends 35 formed thereon and adapted to enter and frictionally engage with correspondingly conical sockets 36 shown as formed by indenting the material of the metallic rear casing part 1 adjacent to the upper end 90 thereof and also adjacent to the rear wall thereof, as appears in the drawings, this construction being more particularly illustrated in Fig. 7. The pivoted wire bail 34 is adapted in its folded position to lie in 100 contact with and partly surround the rear of the rear casing part 1, being correspondingly shaped as appears in Fig. 4, and in its folded position the free middle part of the bail 34 is adapted to engage with a catch 105 37 shown as formed at the bottom and rear of the rear casing part 1 by indenting outward the sheet metal thereof, as clearly appears in Figs. 2 and 3 of the drawings, the resiliency of the spring wire forming the 110 bail 34 adapting it to be snapped over or readily disengaged from the catch 37, which, of course, is rigid. In the inclined position of the frictionally pivoted spring wire bail 34 appearing in Fig. 4, in which it is shown 11 as acting as a prop or support, any slipping of the free middle part of the bail 34 or of the lower end of the inclined casing of the device upon a smooth supporting surface 12 will be prevented by reason of the frictional engagement of the conical ends 35 in the sockets 36, into which they are pressed by the spring tension of the bail 34.

The complete construction of the device has been hereinbefore particularly described, and its operation, manner of use and advantages will now be briefly noted, as follows: First, it may be employed for all of the purposes of an ordinary flashlight or portable electric light not having the fea- 13

tures of my present improvements. Second, the pivoted bail 34 may be extended to form a handle or bail above the device, as appears in Fig. 4, and the device may then be carried 5 in the hand by the extended bail 34, thereby forming an electric lantern. Third, the extended bail 34 provides for attachment of the device to the clothing, for example, by means of a pin or over a button, and the device may 10 be thus employed by trained nurses in making out their reports, by policemen in filling out reports, by motorists for reading road maps, by public speakers for reading their notes, etc. Fourth, the device may be employed 15 as a self-illuminating mirror, and when thus employed may be supported upon a table or the like in the position appearing in Fig. 3 or it may be suspended by the bail 34 from any convenient hook or nail, or the 20 extended bail 34 may be attached by means of a pin to a curtain or the like. With the bail 34 in the folded position, as appears in Figs. 1 and 2, the device may be conveniently carried 25 in a man's coat, vest or trousers pocket, or in a pocket of a lady's garment, or in her hand bag; also the device may be packed in a traveling case, the same as the usual common form of flashlight of similar 30 general appearance but without the features of improvement of my invention.

It is obvious that various modifications may be made in the construction shown in the drawings and above particularly described within the principle and scope of my 35 invention.

I claim:

1. A portable electric light comprising a 40 flat casing divided into front and rear parts in a plane passing between its flat sides, a hinge uniting the two casing parts, battery-supporting means in the rear casing part, a lamp socket fixedly carried by the front casing part at a margin thereof and arranged to expose the lamp at the outside of the flat 45 side of said front casing part, and a mirror fixedly carried by said front casing part and exposed at the outside of the flat side thereof.

2. The invention claimed in claim 1 in 50 which said battery-supporting means comprise a battery-supporting ledge at the bottom, a battery-supporting spring clip at one side, and a battery-supporting abutment member at the top of the battery.

3. The invention claimed in claim 2 in 55 which the casing is of sheet metal and in which said upper battery-supporting member is of electrically conductive material and is insulated from the metallic rear casing part 60 by which it is carried and engages and forms an electrical connection with one of the battery terminals, in combination with an electrically conductive contact spring carried by said insulated electrically conductive upper 65 battery-supporting member and in the path

of and adapted to be engaged by the central terminal of the lamp when the casing is closed.

4. The invention claimed in claim 1 in 70 which said battery-supporting means include an upper electrically conductive battery-supporting abutment member carried by and insulated from the rear casing part and engageable with a contact spring or terminal of the battery. 75

5. The invention claimed in claim 4 in combination with a contact spring which projects from said upper insulated battery-supporting abutment member and is arranged in the path of and adapted to be engaged by the central terminal of the lamp in the lamp socket when the casing is in closed condition. 80

6. The invention claimed in claim 1 in 85 combination with a foldable bail frictionally pivoted to said rear casing part so as to be extended rearwardly and outwardly angularly therefrom, and a catch on said rear casing part for holding said bail in its folded position. 90

7. The invention claimed in claim 3 in combination with superposed insulating plates for insulating the upper battery supporting member from said metallic rear casing part, means for securing said member to the adjacent inwardly exposed insulating plate, tubular rivets for securing together said insulating plates, and plugs of solder within said tubular rivets for securing said insulating plates to the adjacent inner side 100 of said metallic rear casing part. 95

8. The invention claimed in claim 6 in which the bail is of spring material and is provided with conically tapered ends, correspondingly tapered sockets being provided 105 in the rear casing part for receiving said tapered ends of the bail and for frictionally holding the bail in adjusted position by reason of the spring tension of the bail.

9. The invention claimed in claim 1 in 110 which the front flat side of the front casing part is provided with an opening for exposing the mirror, the margin around said opening being embossed outwardly to provide a frame for the mirror and the mirror 115 being inserted from the rear into such frame, in combination with a backing plate for the mirror of larger dimensions than said mirror and secured at its projecting margin to the adjacent inner side of said 120 front casing part so as to cover the back of the mirror and hold the mirror in place in said frame provided in said front casing part.

10. A portable electric light comprising a 125 flat metallic casing divided into front and rear parts in a plane passing between its flat sides, a hinge uniting the two casing parts, battery-supporting means in the rear casing part, a lamp socket fixedly carried by 130

- the front casing part at a margin thereof and arranged to expose the lamp at the outside of the flat side of said front casing part, said battery-supporting means including an upper electrically conductive combined battery-supporting and contact-making device carried by and insulated from the rear casing part and engageable with a contact spring or terminal of the battery and adapted to be engaged by the central terminal of the lamp when the casing is in the closed condition.
11. The invention claimed in claim 10 in which the said combined battery-supporting and contact-making device comprises a comparatively rigid battery-supporting member, and a comparatively flexible contact spring which is engaged by the central terminal of the lamp.
12. A portable electric light comprising a flat metallic casing divided into front and rear parts in a plane passing between its flat sides, a hinge uniting the two casing parts, a lamp socket fixedly carried by the front casing part at a margin thereof and arranged to expose the lamp at the outside of the flat side of said front casing part, a battery-supporting ledge at the bottom of the rear casing part, a battery-supporting spring clip at one side of said rear casing part, an electrically conductive upper battery-supporting member carried by and insulated from the rear casing part at the top of the battery and engaging with one of the battery terminals, and a contact spring carried by said upper battery-supporting member in the path of and adapted to be engaged by the central terminal of the lamp when the casing is in the closed condition.
13. A portable electric light comprising a flat metallic casing divided into front and rear halves in a plane passing substantially midway between its flat sides, said front and rear halves being adapted to be closed together or opened apart, battery-supporting means in the rear casing half, a lamp socket fixedly carried by the front casing half at a margin thereof and arranged to expose the lamp at the outside of the flat side of said front casing half, and a resilient circuit-completing member carried by the rear casing half and insulated therefrom and in electrical connection with a battery terminal and in the path of and adapted to be engaged by the central terminal of the lamp in the lamp socket when the casing halves are closed together.
14. The invention claimed in claim 13 in which a mirror is fixedly carried by said front casing half and is exposed at the outside of the flat side thereof.
15. A portable electric light comprising a flat metallic casing divided into front and rear halves in a plane passing substantially midway between its flat sides, a hinge uniting the two halves, a lamp socket fixedly carried by the front casing half at a margin thereof and arranged to expose the lamp at the outside of the flat side of said front casing half, a mirror fixedly carried by said front casing half and exposed at the outside of the flat side thereof, battery-supporting means in the rear casing half, a circuit-completing member carried by and insulated from the rear casing half at the inside thereof and adapted electrically to connect one of the battery terminals with the central terminal of the lamp in the closed position of the casing parts, and a foldable bail frictionally pivoted to said rear casing half so as to be extended rearwardly and outwardly angularly therefrom.
16. The invention claimed in claim 1 in combination with a foldable bail frictionally pivoted to said battery-containing casing so as to be extended from the flat back thereof rearwardly and outwardly angularly therefrom.
17. A portable electric light comprising a flat casing divided into front and rear halves in a plane passing between its flat sides, a hinge uniting the two halves, battery-supporting means in the rear casing half, a lamp socket fixedly carried by the front casing half at a margin thereof and arranged to expose the lamp at the outside of the flat side of said front casing half, and a mirror fixedly carried by said front casing half and exposed at the outside of the flat side thereof.
18. The invention claimed in claim 17 in combination with a foldable bail or handle movably mounted on said casing so as to be extended therefrom.
- In testimony whereof I have affixed my signature.

BERNARD BENEDICT.
